UNITED STATES PATENT OFFICE.

WALDO A. HANSCOM, OF LONGVIEW, WASHINGTON.

BUCKET.

Application filed June 23, 1926. Serial No. 117,895.

The invention is a bucket for hauling concrete or the like, which is primarily to be used in conjunction with a central mixing plant, which transports mixed concrete, 5 either by truck or car to the job and then dumps its load into this bucket, which normally lays in a horizontal position to receive the load, and which is handled by a crane in such a manner that as it is raised, it will turn 10 over and assume a vertical position, so that it may readily dump its load from a hopper at one end, thereby forming the point of contact between the transportation unit and the forms or grade into which the concrete is to 15 be dumped or upon which it is to be spread as the case may be.

The object of the invention is to provide a means for handling concrete that has been previously mixed, between the transportation 20 unit and the form or grade, which will thoroughly re-mix the concrete as it is dumped into the forms or upon the grade.

Another object of the invention is to provide a bucket of a special design and means 25 for supporting the bucket, which will co-operate to change the position of the bucket as it is handled so that the bucket will thoroughly re-mix concrete or the like as it is handled by it.

30 Another object of the invention is to provide a container for concrete or the like in which the walls are arranged in such a manner that as the concrete is dumped therefrom, the concrete will pass straight downward in a tubular form from the center of the batch while that around the walls will fold into the tubular form as it moves downward and thereby thoroughly re-mix the concrete.

Another object of the invention is to provide 40 a bucket that may be placed in one position to receive a charge of material and which will readily assume another position as it is raised.

A further object of the invention is to provide 45 a bucket for conveying material from one point to another which will agitate the material.

A further object of the invention is to provide 50 a bucket for conveying concrete which has a receiving portion and also a hopper into which the material passes from the receiving portion as the bucket is raised.

And a still further object of the invention is to provide a bucket of the class described 55 which is of a simple and economical construction.

With these ends in view the invention embodies a rectangular shaped bucket having an opening at the top which extends midway of one side, and a hopper at one end 60 formed by converging side walls. The bucket is also mounted upon rails upon which it may be skidded, has a gate at one end and suitable connections for cables.

Other features and advantages of the invention will appear from the following description taken in connection with the drawings, wherein:—

Figure 1 is a side elevation showing the bucket in position for receiving its charge. 70

Figure 2 is an end view looking towards the receiving end and showing the rear portion of a dump truck.

Figure 3 is a view looking towards the opposite end with the gate removed. 75

Figure 4 is a view showing the bucket as it would appear when dumping the material.

Figure 5 is a detail showing the hopper at the end of the bucket provided with baffle plates. 80

In the drawings the device is shown as it would be made wherein numeral 1 indicates the body of the bucket, numeral 2 the receiving end and numeral 3 the hopper.

The body of the bucket is formed with a 85 rectangular shaped casing having the lower corners rounded as shown in Figures 2 and 3. It is understood, however, that the body portion may be round or of any other suitable shape.

The upper side of the body portion is open from one end to the point 4 and the front of the bucket is also open for the same distance and downward to the point 5, which is about midway of the bucket. This opening provides a space into which material may be dumped, as shown in Figure 2. The walls of the bucket converge at the opposite end from the point 6 to the point 7 to form the hopper 3 and at the end of the hopper is a 95 square portion 8 having a segmental gate 9 with a handle 10 to cover the open end. On the under side of the bucket are rails, or beams, 11 which form skids so that the bucket may readily be skidded from one place to another. The body of the bucket is provided with a transverse strap 12 to the ends of which cables or the like may be attached and also longitudinal straps 13, the ends of which extend beyond the end of the casing so that cables may also be attached to them. The 100 interior of the casing may be smooth or pro-

vided with suitable means for agitating material if desired.

It is preferable to have the interior of the bucket smooth, however, it is understood that 5 baffle plates 14 as shown in Figure 5 may be placed around the interior of the bucket if desired to retard the movement of the mixture.

It will be understood that other changes 10 may be made in the construction without departing from the spirit of the invention. One of which changes may be in the arrangement of the receiving or hopper portions of the bucket. Another may be in the location 15 of the opening for the receiving of the material. Another may be in the general design of the bucket. Another may be in the omission of the skid rails, as shown in Figure 4, and still another may be in the general 20 design of the bucket.

The construction will be readily understood from the foregoing description. To use the device, it may first be placed in the horizontal position shown in Figure 1 where it will receive 25 a load of mixed concrete from a truck or car. This concrete will be prepared at a central mixing plant and hauled to the bucket by any suitable means of transportation. The bucket is handled by two lines from a 30 crane as shown in Figure 4, which allows the operator to either hold the bucket in a horizontal, inclined or vertical position. As the crane raises the bucket, it is changed from the horizontal to a vertical position, and thereby 35 turned over so that it will mix its contents, and then as the hopper at the lower end is opened, the concrete in a vertical line above the gate will move downward first and pass 40 out of the gate in the form of a tubular column, and as it moves the concrete around the column will flow toward the center so that the concrete will be again thoroughly mixed. This absolutely guarantees a re-mixed concrete by the time it is ready to go into the form 45 or to the grade and positively takes care of any separation that may be caused in transit from a mixing plant to the job.

The re-mixing process in the three or more turn-overs in the bucket allows the central 50 mixing plant to make concrete in regular proportions, without using any element for retarding its separation, which is now used by

central mixing plants where it takes ten minutes or longer to transport the material to the job. It also eliminates re-mixing the concrete with shovels on grades. 55

This particular type of bucket is also particularly adaptable for placing mixed concrete from transportation units to a grade, as on a paving job where the bucket is under 60 the control of a crane, it may be readily observed that the concrete can easily be spread as the bucket may be readily shifted from one position to another and the hopper opened to permit as much concrete as may be desired 65 passing out of the bucket. It is also adaptable for pouring concrete into forms as for example with a crane having a sixty foot boom, the concrete may be dumped into forms thirty-five or forty feet above the ground, thereby 70 eliminating the elevator and providing a common means for elevating and thoroughly mixing.

The bucket therefore supplies a simple and 75 economical means for handling concrete from transporting means to the forms or grade and also means for thoroughly re-mixing the concrete.

Having thus fully described the invention, 80 what I claim as new and desire to secure by Letters Patent, is:

In a bucket of the class described, a rectangular shaped casing adaptable to rest normally in a horizontal position, a hopper with converging sides extending from one end 85 of the casing, a small rectangular shaped section at the small end of the hopper, a segmental gate forming a closure at the end of the said small section, rails on the under side of the said casing extending lengthwise thereof and curving upward to the small end of the hopper forming skids, a strap around the said casing and adjacent the hopper end, suitable cables, means for attaching the cables to the 90 ends of the strap, other cables somewhat shorter than the former cables, and means for attaching the said other cables to the end of the casing opposite to the hopper, said cables being adaptable to upend the bucket 95 as it is raised by them, and said bucket having an opening in a portion of one side and of the top. 100

In testimony whereof I affix my signature.

WALDO A. HANSCOM.
